UNITED STATES PATENT OFFICE.

LEVI F. SHERFEY AND JOSEPH E. SHERFEY, OF AVOCA, NEBRASKA.

EAR-CORN CONVEYER FOR CORN-SHELLERS.

SPECIFICATION forming part of Letters Patent No. 671,453, dated April 9, 1901.

Application filed November 26, 1900. Serial No. 37,836. (No model.)

To all whom it may concern:

Be it known that we, LEVI F. SHERFEY and JOSEPH E. SHERFEY, citizens of the United States, residing at Avoca, in the county of 5 Cass and State of Nebraska, have invented a new and useful Ear-Corn Conveyer for Corn-Shellers, of which the following is a specification.

Our invention is an improved ear-corn conveyor for corn-shellers adapted to convey corn from a corn-crib or the like to a corn-shelling machine to feed the latter, the object of our invention being to provide an improved ear-corn conveyer which may be used in connection with a corn-shelling machine of any variety and which may be disposed at any required angle, with its inner end either within or out of the corn-crib.

Our invention consists in the peculiar construction and combination of devices herein-after fully set forth and claimed.

In the accompanying drawings, Figure 1 is a side elevation, partly in section, of an ear-corn conveyer embodying our improvements, 25 showing the same in operative position to convey corn from a crib to a corn-shelling machine. Fig. 2 is a partial top plan view of our improved ear-corn conveyer, showing the same mounted on the feed-elevator of a corn-shelling machine. Fig. 3 is a detail view of 30 the inner end of our improved ear-corn conveyer. Fig. 4 is a detail perspective view of the standards to which the upper end of our improved ear-corn conveyer is pivotally and 35 detachably connected.

To enable our invention to be readily understood, we have in Fig. 1 of the drawings shown our improved ear-corn conveyer A in connection with a corn-crib B and a corn-shelling machine C. The machine is of any suitable construction and forms no part of our present improvements and is provided with the usual inclined feed-elevator D and with a power-shaft E, from which we derive 45 power to operate our improved ear-corn conveyer.

In the embodiment of our invention we provide a pair of standards 1, which are curved on their outer sides, as at 2, concentrically, or 50 nearly so, with the shaft E, the said standards being attached by bolts or other suitable devices to the sides of the feed-elevator D of

a corn-shelling machine. In the form of our invention here shown the standards 1 comprise the arch-shaped or segmental bars 3, 55 formed integrally and connected together at their upper ends by an intermediate transversely-disposed strap 4, which forms a stop at the upper ends of the bars 3, the latter being provided on their outer sides, at their 60 upper ends, with recesses 5, adapted to form bearings for a shaft hereinafter described. Near their lower ends the said bars 3 are provided with stop-hooks 6. Said bars 3 are braced and supported by strap-arms 7. The said 65 standards, as will be understood, will be readily attached to the sides of the feed-elevator of the corn-shelling machine and may be adapted to the shape and inclination thereof.

The trunk or trough of our improved ear-corn conveyer A is of suitable length and breadth and comprises the side boards 8 and connecting-board 9, the latter being disposed about midway between the sides of the side boards 8, the said trunk or trough being practically H-shaped in cross-section. In the upper end of the conveyer-trunk is journaled a shaft 10, the ends of which project beyond the sides of the conveyer-trunk and rest upon the arc-shaped sides of the standards 1 and 75 80 are adapted to bear and rotate either in the recesses 5 at the upper sides of said standards 1 or on the hooks 6 near the lower sides of said standards. To the said shaft 10 is keyed a sprocket-wheel 11, which is connected to a sprocket-wheel 12 on the power-shaft 75 85 E of the corn-shelling machine by an endless sprocket-chain 13. The said shaft 10 is further provided with sprocket-wheels 14, which engage and operate the endless chains 15 of 90 the endless conveying element of the conveyer. The said chains are connected together by the flights 16, said chains and flights operating on the board 9 and the said chains engaging suitable sprocket-wheels on 95 a shaft 17 near the lower or inner end of the conveyer-trunk, which shaft 17 is journaled in suitable bearings in the side boards 8 of the conveyer-trunk.

It will be understood from the foregoing 100 that our improved conveyer has its upper end pivotally mounted on the standards 1 and adjustable thereon and that the lower inner end of our conveyer may be raised or low-

ered, as may be required, to dispose the same either on the ground immediately below the door of a corn-crib, as shown in full lines in Fig. 1, or to run the same into the door of a 5 corn-crib and support it on the floor thereof, as indicated in dotted lines in Fig. 1. The inner free end of the trunk of the conveyer is provided on its upper side with flared boards 18, which facilitate the feeding thereof with 10 ear-corn from the crib.

When the corn-shelling machine is in operation, power is conveyed from the shaft E thereof to the shaft 10 of the ear-corn conveyer by the sprocket-wheels 11 12 and chains 15 13, thereby actuating the endless conveying element of our conveyer and causing the ear-corn to be conveyed from the crib and discharged into the feed-elevator of the corn-shelling machine.

20 When the crib is full, or nearly so, the inner free end of the trunk of our conveyer is disposed on the ground just below and opposite the door of the crib, as shown in full line in Fig. 1, so that when the door is opened the 25 corn will be fed by gravity into the conveyer. When the corn will no longer flow and requires to be shoveled into the conveyer, the inner end of the trunk thereof is disposed on the floor of the crib, as indicated in dotted 30 lines in Fig. 1, to facilitate the shoveling of the corn thereinto.

Having thus described our invention, we claim—

1. In combination with a corn-shelling machine having a feed-elevator and a power-shaft, standards secured on the sides of the 35 said feed-elevator and having curved faces concentric with said power-shaft and bear-

ings at the ends of said curved faces, an endwise-movable corn-conveyer comprising a trunk and an endless traveling conveying element, the latter having a shaft journaled in said trunk, bearing on said curved faces of the standards and shiftable when said conveyer is moved endwise into the bearings at 45 either end of said curved faces, and thereby forming a pivotal and adjustable connection between said conveyer and the corn-shelling machine, and operative connections between said shaft and the power-shaft of the corn-shelling machine, substantially as described.

2. In combination with a corn-shelling machine having a feed-elevator and a power-shaft, standards secured on the sides of the 50 said feed-elevator and having bearings concentrically disposed with relation to said power-shaft, an endwise-movable ear-corn conveyer comprising a trunk and an endless traveling conveying element, the latter having a shaft journaled in said trunk, adjustable in the bearings of said standards and thereby forming a pivotal and adjustable connection between said conveyer and the corn-shelling machine to permit of the endwise adjustment of said conveyer, and operative connections between said shaft and the power-shaft of the corn-shelling machine, substantially as described.

In testimony that we claim the foregoing as our own we have hereto affixed our signatures 70 in the presence of two witnesses.

LEVI F. SHERFEY.
JOSEPH E. SHERFEY.
